UNITED STATES PATENT OFFICE.

CHARLES HENRY BROWN, OF BRECKENRIDGE, TEXAS.

COLLAPSIBLE SOCKET.

Application filed December 12, 1921. Serial No. 521,730.

To all whom it may concern:

Be it known that I, CHARLES H. BROWN, a citizen of the United States, and resident of Breckenridge, county of Stephens, and State 5 of Texas, have invented certain new and useful Improvements in Collapsible Sockets, of which the following is a specification.

This invention relates to collapsible sockets especially adapted for use in removing 10 various objects from wells.

An important object of this invention is to provide a collapsible socket wherein the jaws are provided at their forward portions with enlargements or offsets capable 15 of insertion into a narrow space between the object to be removed and the well.

A further object is to provide a collapsible socket having novel means whereby the jaws of the same may be securely engaged with 20 the sides of the object to be removed when the jaws have reached the limit of their forward movement.

A further object is to provide a collapsible socket which is simple to operate, of highly 25 simplified construction and cheap to manufacture.

Other objects and advantages of the invention will be apparent during the course of the following description.

30 In the accompanying drawings, forming a part of this application and in which like numerals are employed to designate like parts throughout the same,

Figure 1 is a vertical sectional view 35 through the improved collapsible socket, the same being shown in its inoperative position, or the position which it normally occupies.

Figure 2 is a horizontal sectional view 40 taken on line 2—2 of Figure 1.

Figure 3 is a horizontal sectional view taken on line 3—3 of Figure 1.

Figure 4 is an end elevation, the view illustrating the forward ends of the jaws.

45 Figure 5 is a detail sectional view illustrating the clamping sleeve in its inverted position so as to cause the jaws to grip all objects.

Figure 6 is a vertical sectional view 50 through a modified form of the invention, the view illustrating the same in its inoperative position.

Figure 7 is a similar view of the device 55 illustrated in Figure 6, the view illustrating the same in its operative position.

Figure 8 is a detail sectional view illustrating a modified form of article engaging member.

Figure 9 is a fragmentary vertical sectional view through a modified form of the 60 invention, the same being shown in its inoperative or normal position.

Figure 10 is a perspective of a sleeve embodied in the invention.

Figure 11 is a horizontal sectional view 65 taken on line 11—11 of Figure 9.

Figure 12 is a horizontal sectional view taken on line 12—12 of Figure 9.

Figure 13 is an end view of the sleeve 70 illustrated in Figure 10.

In the form of the invention illustrated in Figures 1 to 5 inclusive the barrel is designated by the numeral 10 and is provided at its rear end with a shank 11 having its rear terminal portion 12 threaded for engagement with the jars employed for lowering 75 the device into a well.

The shank 11 may be provided with flattened sides which provide a means whereby the jaws of a wrench may be engaged with 80 the device for turning the tool onto the lowering means or else for removing the same. As illustrated in Figure 1 the barrel 10 is provided intermediate its ends with an internal abutment 13 welded or otherwise secured in position and having a centrally arranged opening for the reception of the rod 14 formed on the rear end of the gripping means. The rod 14 has its rear terminal portion threaded and engaged by a nut 15 85 held in position by means of a cotter key 16. The barrel 10 is provided at one side with an opening 17 which affords access to the cotter key 16 and the nut 15 so that the gripping member may be attached or disconnected whenever desired.

A coiled spring is mounted on the rod or plunger 14 and has one end in contact with the abutment 13 and the other end in contact with a shoulder 19 formed intermediate the ends of the movable gripping device.

The forward portion of the rod is provided with a plurality of spring arms 21 gradually increased in cross sectional area toward their forward ends and provided on their inner sides with teeth 22 adapted for engaging a portion of an object to be removed from the well. The arms 21 which may be of spring metal and of a suitable 105 110

stoutness are segmental in cross section and cooperate in the formation of a gradually restricted opening for the reception of a portion of the article to be removed.

- 5 When the improved socket is lowered into a well the forward ends of the spring arms are engaged with the object to be removed and the object is received within the gradually restricted opening formed by the arms.
- 10 When the spring arms 21 reach the limit of their forward movement the barrel 10 continues its forward movement by the weight of the jars and the spring which resists this movement of the barrel is retracted where-
- 15 by the rod 14 moves into the rear portion of the barrel and contacts with the rear end wall 25 of the barrel. However, when the barrel 10 begins its forward movement with relation to the spring arms it contacts with
- 20 a clamping sleeve 26 slidable on the arms and when the sleeve 26 is advanced said arms are drawn together so that the object confined between the arms is tightly and securely gripped. The forward movement of
- 25 the barrel 10 cannot force the sleeve 26 off the forward ends of the spring arms as the rear end of the rod 14 abuts the rear end wall 25 before the sleeve 26 could possibly be forced off, the end of the spring arms.
- 30 Also the forward portions of the spring arms are offset as indicated at 27 so as to form shoulders 28 which engage the forward edge of the sleeve 26.

It will be seen with reference to Figure 1
35 that the sleeves or binding elements 26 are arranged rearwardly of the offset portions 27 so that the offset portions 27 may fit between the object to be gripped and the wall of the well. As is known the space between
40 the object to be gripped and the wall of the well is very slight and by locating the clamping device 26 rearwardly of the offset portions 27 the thickness of each spring arm does not have to be decreased to permit it
45 to fit within the narrow space. It is therefore apparent that the offsets 27 not only form a means whereby the forward movement of the sleeve 26 is limited, but also permits the device to be engaged with objects
50 confined within the well, which objects lie close to the side of the well.

When the device is being advanced on an object the spring 18 yieldably holds the barrel 10 in its retracted position, and when
55 the forward end of the barrel engages the sleeve, the sleeve is advanced for forcing the spring arms together. The sleeve 26 has its bore gradually enlarged toward one end so that the same when inverted in the manner
60 illustrated in Figure 5 causes the spring arms 22 to grip extremely small objects. In other words the sleeve 26 when inverted in the manner illustrated in Figure 5 decreases the space between the jaws.

65 In the form of the invention illustrated

in Figures 6 and 7 the barrel is designated by the numeral 30 and is provided intermediate its ends with an annular abutment 31 through which a rod 32 is extended. The rod 32 has its forward end enlarged as indicated at 33 and a plurality of spring arms 34 are joined with the enlarged portion 33 by welding or other suitable means. As illustrated in Fig. 6 the coiled spring 35 which is mounted on the rod 32 between the 70 enlargement 33 and the abutment 31 urges the spring arms 34 to their advanced positions.

The spring arms 34 diverge toward their forward ends and have their terminal portions extended inwardly as indicated at 350. A collar 36 is slideable on the spring arms 34 and is advanced on the sleeve 36 when the barrel 30 is advanced. The forward movement of the sleeve 36 is however, limited by 85 a plurality of shoulders 37 formed on the spring arms.

In the use of this form of the invention the same is passed through the well casing and as soon as it passes out of the lower 90 end of the well casing the arms spread and contact with the wall of the well so as to be in a position to grasp the object to be removed. By the inwardly extending terminal portions 350 of the arms 34 objects that are lying flat on a hard bottom may be engaged. The arms 34 scrape the bottom of the well each time a thrust is placed on the spring. The arms 34 may be sufficiently flexible to enable the same to conform somewhat to the 100 shape of irregular objects or groups of objects to be removed from the well.

Figure 8 illustrates a modified form of the invention especially adapted for use in fishing for sucker rods. This view illustrates that the spring arms 40 may be provided with offset forward end portions 41 having gripping teeth 42 adapted to be engaged with a portion of the sucker rod. The offsets 41 define shoulders 44 within the opening or 105 socket provided by the spring arms, which shoulders are adapted to be engaged with the shoulder on the sucker rod. The spring arms 40 are formed rearwardly of the socket formed by the offset with a second socket 45 110 of a reduced diameter, the walls of the said socket 45 being threaded for engagement with the pin of the sucker rod. It is thus seen that the device illustrated in Figure 8 is provided with a double gripping means 120 for the sucker rod and when the ring is advanced the walls of the several sockets will be forced into engagement with the sucker rod and the pin of the same.

With reference to Figures 9 to 13 inclusive it will be apparent that the invention idea involved may be carried out in connection with a plurality of spring arms 46 extended into a barrel 47 and having rods 49 upon which springs 50 are mounted. The 125 130

rear ends of the springs 50 contact with a disk-shaped abutment 51 and the forward ends of the springs contact with the shoulders formed at the rear ends of the spring arms. The spring arms 46 may be welded or otherwise secured at their rear ends to the sides of the rods 49 thereby defining the shoulders with which the forward ends of the springs 50 are engaged. A guide disk 54 may be connected to the abutment 51 by means of a plurality of rods or links 55.

As illustrated in Figure 9 a sleeve 58 is mounted on the spring arms 46 and is provided with an inwardly extending end wall 59 having notches 60 to receive the spring arms 46 whereby the spring arms are prevented from moving laterally with relation to each other when being engaged with an object. The sleeve 58 is provided at its rear end with radially arranged apertured ears 62 which slidably receive guide rods 63 secured to the forward end 65.

The invention as illustrated in Figure 9 is especially adapted for use in removing underreamer lugs, and the like, and as the several spring arms 46 are independently and separately urged to their advanced positions any one of the arms 46 may move rearwardly with relation to the other spring arms. This feature permits the device to more readily conform to the shape of the object to be removed. The forward ends of the spring arms may be formed with inwardly directed claws 68 which form a means for gripping various articles.

Further by reason of the particular arrangement illustrated in Figure 9 the object to be removed is subjected in a way to a raking action and is forced to the center of the well so that the further downward movement of the device permits all of the arms to be engaged with the object.

By using the springs to hold the spring arms 46 down and by using long stroke jars the tool may be set on the bottom of the hole in cases where mud has settled and buried the underreamer lugs and by driving slightly so as not to close the arms, the arms may be moved through the mud without closing the same.

Having thus described the invention, what is claimed is:—

1. A fishing tool comprising a barrel having its intermediate portion provided with an internal abutment, a rod slidable through and guided by said abutment, a plurality of spring arms secured to the forward portion of said rod and having article gripping means, a coiled spring confined between said arms and said abutment, and a sleeve surrounding said spring arms in advance of said barrel and adapted for closing the same.

2. A fishing tool comprising a barrel having its intermediate portion provided with

an abutment, a rod slidable through said abutment, a plurality of spring arms secured to the forward portion of said rod and having article engaging means, a coiled spring confined between said arms and said abutment, and a sleeve surrounding said spring arms and adapted for closing the same; the bore of said sleeve being gradually decreased toward one end. 70

3. A fishing tool for wells comprising a barrel having a socket provided with a rear end wall, a rod slidable in said socket, said socket being provided intermediate its ends with an abutment, a plurality of spring arms secured to the forward end of said rod and having means for gripping an article to be removed, and a sleeve surrounding said spring arms and slidable on the same, the forward end of said barrel being adapted to engage said sleeve to advance the same, 80 the rear end of said rod being adapted to engage the rear end of said socket whereby the forward movement of said sleeve is limited. 85

4. A device of the class described comprising a barrel having an abutment, a rod slidable through said abutment, a plurality of spring arms secured to the forward end of said rod and having their forward portions provided with offsets defining shoulders and gripping means, said gripping means being adapted for engagement with an article lodged within a well, a sleeve slidable on said spring arms and limited in its forward movement by said offsets, the 95 forward end of said barrel being adapted to engage said sleeve to advance the same. 100

5. A fishing tool for wells comprising a barrel having a socket provided with a rear end wall, a rod slidable in said socket and having a plurality of article gripping arms, and a sleeve surrounding said arm, the barrel being adapted to engage the sleeve to advance the same on said arms, the rear end of said wall being in the path of travel and adapted to be engaged by said rod whereby the movement of the sleeve forwardly on said arm is limited. 110

6. A fishing tool for wells comprising a barrel having a socket provided with a rear end wall, a rod slidable in said socket and having a plurality of article gripping arms, a sleeve surrounding said arm, the barrel being adapted to engage the sleeve to advance the same on said arms, the rear end of said wall being in the path of travel and adapted to be engaged by said rod whereby the movement of the sleeve forwardly on said arm is limited, the intermediate portion of the barrel being provided with an internal abutment slidably receiving said rod, and a spring mounted on said rod between the rear ends of said arms and said abutment and urging the arms forwardly. 120 125

CHARLES HENRY BROWN.
